UNITED STATES PATENT OFFICE.

JOSEPH REIDHARD, OF CELINA, OHIO.

DITCHING-MACHINE.

SPECIFICATION forming part of Letters Patent No. 254,376, dated February 28, 1862.

Application filed August 10, 1881. (No model.)

To all whom it may concern:

Be it known that I, JOSEPH REIDHARD, of Celina, in the county of Mercer and State of Ohio, have invented certain new and useful 5 Improvements in Ditching-Machines; and I do hereby declare that the following is a full, clear, and exact description of the invention, which will enable others skilled in the art to which it appertains to make and use the same, 10 reference being had to the accompanying drawings, which form a part of this specification, and in which—

Figure 1 is a longitudinal vertical section. Fig. 2 is a vertical transverse section through 15 the front axle with its standards and adjustable saddle. Fig. 3 is a perspective view of the front end of the dirt chute or elevator with its adjustable plow and appurtenances. Fig. 20 4 is a similar view of the discharge or unloading apparatus at the end of the chute, and Fig. 5 is a top view of the complete machine.

Similar letters of reference indicate corresponding parts in all the figures.

My invention has relation to machines for 25 digging ditches for drain-tile or for other purposes; and it consists in an improved construction and combination of parts of a machine of that class, as hereinafter more fully set forth, having for its object to produce a machine 30 which can be built at comparatively small expense, be easily managed, and which is adapted to do quick and efficient work irrespective of the nature of the soil in which it is to be used.

In the annexed drawings, A represents the 35 front axle of my machine, which has a tongue or pole, B, and wheels C C. It also has a bolster, A', into which are mortised parallel uprights D D, connected by a cross-bar, D', at top, upon which is journaled in suitable bearings 40 a pinion, E, having a crank, E', which said pinion meshes with a rack, F, that slides through a slot in the cross-bar D', and is connected at its lower end, between the uprights or standards D D, to the yoke G' of the saddle-beam 45 G, the sides of which are grooved to slide upon the uprights D D.

H is a hinged pawl, which by engaging with notches in the back of the rack F serves to retain this and its saddle G G' in its adjusted 50 position. To the back of the axle A is hinged or pivoted the balance-yoke I, the use of which will be hereinafter explained.

K is the hind axle, which supports the frame L of the ditching apparatus proper, and has the driving-wheels M M, one of which has two 55 and the other one concentric spur-pulleys at the inner face, as shown respectively at N, N', and N² in the top view, Fig. 5.

O' O' are endless, chains which pass around the pulleys N and N², and also around spur-pulleys (shown at P' P') at the outer ends of a drum, Q, which is journaled in the lower part of frame L, back of its axle K, and supports the rear end of the endless carrier or chute apron R, which is provided with equidistant buckets R'. The forward end of apron R R' passes around another drum or shaft, S, in the forward end of the elevator-chute T, the rear end of which is hinged in the rear end of frame L upon bolts L'. 70

U is the plow, the shape and construction of which will readily be understood by reference to Figs. 1 and 3 of the drawings. It is made of iron, with an inclined share having a steel point, the parallel vertical sides of the 75 plow forming rounded colters U', which are made with sharp steel edges. The forward end of the chute, with its apron, projects in between the flanged sides of the plow below its inclined share, where it is hinged by trunnions 80 S', projecting from the ends of the drum S, between the sides of the plow, so that the latter may have a vibratory motion independent of the chute with its apron.

The elevation of the pointed plowshare is 85 adjusted and maintained in its adjusted position by means of a bar, V, which projects up through a slotted bolster, V', secured at the rear end of the tongue L² of frame L, which said tongue also supports the driver's seat L³. 90 When the machine is in use the forward end of tongue L² is inserted into the vertically-adjustable saddle G G', as shown in the drawings, so that by elevating the saddle by means of the crank E' and pinion E the forward end of 95 frame L, with its chute and plow, is elevated proportionately, while it will be seen that the forward end or share-point of the plow may be adjusted independently of the chute, to which the plow is hinged, by the bar V, which is fixed in any given position, to keep the plow properly "set," by a pin, V², inserted through coinciding perforations in the block or bolster V' and bar V.

In order to equalize the draft or pull upon frame L and the plow U, I employ a bifurcated arm, W, the forked end of which is pivoted in the sides or colters of the plow, while its outer end is hinged on a bail or clevis, W', which is pivoted in the lower end of the balance-yoke I. In the upper end of this yoke is in like manner pivoted the outer link of a chain, X, the inner end of which is fastened in the under side of tongue L² of frame L.

The dirt is discharged at the rear end of the chute T R into a receiver, Y, appended to the back part of the frame, in which is arranged a vertical revolving shaft, Z, having four horizontal arms, a, at its lower end. The shaft Z, which is inserted through suitable bearings in the rear end of frame L, has a pinion, b, at its upper end, which meshes with a worm or spiral, c, at the outer end of which is a spur-pulley, d, operated by the chain O from pulley N'. The rotating arms a discharge the dirt sideways from the receiver or platform Y out over

the edges of the ditch, the dirt being prevented from falling back into the ditch by a guard or shield, e, at the rear end of platform Y. 25

Having thus described my invention, I claim and desire to secure by Letters Patent of the United States—

The combination of frame L, hinged chute T, having bucket-apron R R', hinged plow U U', 30 setting-bar V, equalizing-bar W, and front carriage, A B C, provided with the balance-yoke I, connected at opposite ends to bar W and chain X, which said chain is fastened in the frame L, substantially as and for the purpose 35 herein shown and specified.

In testimony that I claim the foregoing as my own I have hereunto affixed my signature in presence of two witnesses.

JOSEPH REIDHARD.
